Anson M'Coll and Norman M'Coll
Sellers Patent

The Schedule is referred to in this Sellers Patent and making part of this same containing a description in the words of the said Anson M'Coll and Norman M'Coll themselves of their improvement in extracting alcohol from common proof spirits by the use of steam.

The principle we use for extracting alcohol from common proof spirits is, by enclosing a still within a wood or metallic tubef which still contains . . . . . the common proof spirits, and likewise a worm or single tube which may be the side of the still and extend to the bottom. The steam is generated in the common way and when let on it enters the worm or tube in the still. If the worm, it passes through its windings, and through the bottom of the still into the space between the still and reflux which encloses it, but if the steam enter the other tube it discharges within the still. The steam pipe which leads from the boiler extends down to the bottom of the reflux from which the steam is taken into the reflux which encloses the still, rendering thereby assistance to that which passes thro' the worm in the still, both of which set the spirits in the still boiling, or either one of those pipes which discharge the steam between the still and reflux, may answer the purpose alone. The spirit, as it leaves the still, enters another still, which is like the first enclosed, and by the heat of the steam or spirit from the first still, together with the steam taken from the first reflux, which envelopes the still both of which set the second still boiling, or either one alone may do it. As the spirits leave this still, it enters the still worm and is drawn off at bottom.

The reflux enclosing the stills, have vents to discharge the surplus steam and water. This principle may be used in extracting spirits of turpentine, refining sugar, making varnish, and is useful for dies of cloths, for planking and colouring.

United States Patent

Patent No.: X4711

Heat, and is applicable in many chemical operations, where fire directly applied is dangerous, all of such operations your petitioners claim as their right.
